(57) **CLAIM**

The ornamental design for a computing device with graphical user interface for communicating health-related messages regarding ventilated patients, as shown and described.

DESCRIPTION

FIG. 1 is a front view of a computing device with graphical user interface for communicating health-related messages regarding ventilated patients; and,

FIG. 2 is a front view of a second embodiment thereof. The outer-most broken line rectangle in each figure illustrates a computing device housing a display screen. The remaining broken lines illustrate portions of the graphical user interface. None of the broken lines form part of the claimed design.
